Primary Examiner — Kevin Rudzinski*Assistant Examiner* — Sean D Lough(74) *Attorney, Agent, or Firm* — Dorsey & Whitney LLP(57) **CLAIM**

The ornamental design for the illumination diffuser, as shown and described.

DESCRIPTION

FIG. 1 is a perspective view of an illumination diffuser, according to a first embodiment;

FIG. 2 is a side view of the illumination diffuser, according to a first embodiment;

FIG. 3 is a top view of the illumination diffuser, according to a first embodiment;

FIG. 4 is a bottom view of the illumination diffuser, according to a first embodiment;

FIG. 5 is a perspective view of an illumination diffuser, according to a second embodiment;

FIG. 6 is a side view of the illumination diffuser, according to a second embodiment;

FIG. 7 is a top view of the illumination diffuser, according to a second embodiment; and,

FIG. 8 is a bottom view of the illumination diffuser, according to a second embodiment.

The broken lines present in the second embodiment (FIGS. 5-8) illustrate portions of the illumination diffuser that form no part of the claimed design.

1 Claim, 4 Drawing SheetsUS D771,302 S
